FRAME FOR CHINAWARE OR SIMILAR ARTICLE

Donna D. Littlepage, Fort Worth, Tex.

Substituted for abandoned design application Serial No. 28,495, January 12, 1954. This application April 2, 1956, Serial No. 40,865

Term of patent 14 years

(Cl. D29—20)

Figure 1 is a front elevational view of a frame for chinaware, or similar article, embodying my new design;

This application is a substitution for applicant's earlier application, Serial No. D-28,495, filed January 12, 1954, which is now abandoned.

I claim:

The ornamental design for a frame for chinaware, or similar article, substantially as shown and described.
